UNITED STATES PATENT OFFICE.

FRANK OBERST, OF NEW YORK, N. Y., ASSIGNOR TO SONORA PHONOGRAPH COMPANY, INC., A CORPORATION OF NEW YORK.

COMBINATION RADIO AND PHONOGRAPH APPARATUS.

Application filed September 6, 1924. Serial No. 736,233.

This invention relates generally to a combined phonograph and radio receiving set, and more particularly to an instrument in which the phonograph and radio receiving set are contained in the same cabinet, and the employment in such combination of elements capable of and intended for employment in a phonograph construction, and co-ordinately involves either or both, the association with or the attachment to the whole or to a part of a phonograph construction, of mechanism whereby the sound amplifying portions of a phonograph can be employed as a common amplifier for amplifying audio frequency in connection with radio receiving apparatus and for sound reproduction from a phonograph record.

For purposes of illustration my device is shown for use in a cabinet containing the operating parts of a phonograph together with a complete radio receiving set including batteries, radio reproducer and necessary wiring. However, it is understood that my device may be applied to a phonograph cabinet alone, with the radio receiving set located at any convenient point so long as the necessary electrical connection is made with the radio reproducer included in my phonograph cabinet.

One of the objects of my invention is the construction of a combined phonograph and radio apparatus, utilizing a common amplifier having means to connect or disconnect the radio sound producing means or the phonograph producing means from the said amplifier.

A further object of my invention is to provide a simple, rugged device which will allow the playing and amplification of phonograph sounds in the usual way, without any tone losses, and by an easy manipulation at the will of the operator, the same phonograph horn may be used to amplify a radio reproducer also without tone losses.

A further object of my invention is the construction of valve mechanism which is always positive in operation, easily manipulated and which will not get out of order.

Another object of my invention is to provide a device which, when manipulated at the will of the operator, will, by valve action, interrupt the free passage of sound from the phonograph reproducer to the horn, and simultaneously open a free passage for the sound from the radio reproducer and with a

reverse manual movement of the control mechanism will produce a reverse simultaneous result.

A further object of my invention is to provide a simple device subject to the will and easy manual control of the operator, whereby the volume of sound issuing from the horn or amplifier, produced either by the phonograph or radio reproducer, may be progressively increased to the maximum ability of either reproducer, or decreased to a mere whisper, or either reproducer may be shut off entirely. All these effects may be secured without any tone losses whatsoever, except such tone losses as are brought about at the express desire of the operator.

Another object of the invention is to provide an instrument to produce good sound reproduction of both kinds, and in which the same horn may be used for both purposes.

Another object is to provide an instrument in which the receiving set and the phonograph are compactly arranged in a cabinet of attractive appearance. The combining of these elements is to economize space and to utilize an amplifier for both purposes.

Another object of the invention is to provide an improved combination phonograph and radio, which will be compact, simple in construction, economical to manufacture, efficient in operation, attractive in appearance and inexpensive to manufacture.

With these and other objects in view, to be more fully set forth hereinafter, the invention consists in the novel construction, combination of elements, and arrangement of parts, which will be exemplified in the operation and construction herein described in the following specification and illustrated in the accompanying drawings.

The invention will first be described in connection with the accompanying drawings, wherein similar reference characters are used to designate corresponding parts throughout the several views, and more specifically defined and indicated in the appended claims.

Attention is directed to the drawings in which—

Fig. 1 is a front elevation of my invention mounted in a cabinet containing a phonograph and a radio receiving set, with the front panel of the cabinet removed and

various parts broken away to show the arrangement of the elements;

Fig. 2 is a plan view of the same with the top of the cabinet removed;

5 Fig. 3 is a detailed central sectional elevation of my device in position to give amplification from the phonograph reproducer, and to exclude possible sounds from the radio reproducer;

10 Fig. 4 is the same as Fig. 3 with the parts in position to give amplification from the radio reproducer to the exclusion of possible sounds from the phonograph reproducer;

15 Fig. 5 is a detailed plan view of my device showing the method of mounting and control handle or operating mechanism.

For the purpose of illustration, I show my invention mounted in a cabinet 1, bisected by a main vertical partition 2 into a 20 radio section and a phonograph section, as shown in Fig. 1.

The radio section is bisected by horizontal partition 3 forming chamber 4 containing radio receiving set 5, and chamber 6 containing radio batteries 7.

25 The phonograph section is bisected by horizontal partition 8, commonly called the "motor board" into chambers 9 and 10. Chamber 9 contains the usual parts of the phonograph found above the "motor board", i. e., phonograph reproducer 11, adapted to track on record (not shown) on turn-table 12, and attached to tone-arm 13. Chamber 10 contains my device, which I shall call, 30 for convenience, a swinging damper valve chamber 14, which also forms the small end of single amplifier or horn 15 (Fig. 2), the larger end of which extends to the open air at the front of the cabinet, as will be readily 35 understood. Chamber 10 also contains spring motor box 16 housing the operating parts for revolving turn-table 12 and hand crank 17 for winding the motor. Attached to the side of chamber 14 is radio 40 reproducer arm 18 having attached to its smaller end radio reproducer 19 wired to radio receiving set 5 by suitable wiring (not shown). Passing through a hole in rear panel 20 is partially rotating control handle 21, whose function will be more fully 45 explained hereafter.

Having now generally located the elements, I will proceed with a detailed description of my invention with particular 50 reference to Figs. 3 to 5. For purposes of illustration, chamber 14 is shown as a continuation of small end of horn 15 (Figs. 3 and 4), although it is understood that a 55 separate chamber to which small end of horn 15 may be secured could be used. Chamber 14 is firmly secured to motor board 8 as by wood screws 22 (Fig. 5), or any 60 other suitable means.

Aligning with the open end of chamber 14 65 is opening 23 in motor board 8, having tight-

ly fitted therein annular flanged ring 24 in which tone arm 13 is mounted so as to freely swing in a horizontal plane.

Secured to the side of chamber 14, as by means of screws 25 through holes in flange 70 in radio arm 18, aligning with opening 26 is chamber 14, as will be readily understood.

Extension 27 of control crank 21 projects into chamber 14 through suitable holes provided in panel 20 and chamber 14, which 75 also serve as bearings for said extension 27. Firmly secured to, so as to rotate with, extension is swinging damper valve 28, covered with suitable sound deadening material such as baize or felt, which is pivoted at 29 (Fig. 5). Thus, by means of control crank 21 and extension 27, damper valve 28 may be swung from a horizontal position (Fig. 4) to a vertical position (Fig. 3), or 80 any intermediate point through an arc of 85 ninety degrees.

If it is desired to play the phonograph, control crank 21 is swung to carry damper valve 28 into position as in Fig. 3, and a 90 clear uninterrupted and continuous passage for phonograph sound is thereby provided between tone arm 13, opening 23 and the horn or amplifier 15, while damper valve 28 effectively cuts off any extraneous sound which might arise in the radio reproducer. 95 The damper valve 28, in closing opening 26, also prevents any phonograph tone losses. To modify the volume of phonograph sound it is only necessary to slowly swing control crank 21 through its arc. Thus damper 100 valve 28 gradually reduces the passage through which the sound flows into horn 15.

To amplify sound from the radio reproducer, control crank 21 is swung to bring 105 damper valve 28 into the position shown in Fig. 4, thus providing a clear passage for the radio reproducer sound through opening 26 into chamber 14, thence out through horn 15, damper valve 28 meanwhile obstructing extraneous sound arising 110 from the phonograph reproducer and also closing opening 23, thus preventing all radio reproducer tone losses. Radio reproducer sounds may also be modified, if desired, by slowly swinging control handle 21 back 115 through its arc, as will be clear.

In accordance with the provisions of the patent statutes, I have described my invention together with the construction which I now consider to represent the best embodiment thereof, but I desire it understood that my invention is not confined to the particular form shown and described, the same being merely illustrative, and that the invention can be carried out in other ways without departing from the spirit of my invention; and, therefore, I claim broadly the right to employ all equivalent instrumentalities coming within the scope of the appended claims, and by means of which ob- 120 125 130

jects of my invention are attained, and new results accomplished, as herein set forth, as it is obvious that the particular embodiments herein shown and described are only 5 some of many that can be employed to attain these objects and accomplish these results.

Having now described my invention, what I claim and desire to secure by Letters Patent, is:

- 10 1. In a device of the character described, a rectangular chamber, an amplifier hung from the bottom of and opening into said chamber, a phonograph tone arm mounted upon and opening into the top of said chamber, a telephone receiver supported by and opening into a side of said chamber adjacent the top, and a valve pivoted in the angle formed by the top and the side containing the opening of said telephone receiver
- 15 20 and adapted to be swung on its pivot from a position parallel to the top to a position parallel to said side whereby to close alternatively the openings to said tone arm and said telephone receiver.

2. In a device of the character described, 25 a rectangular wooden box, an amplifier hung from the bottom of said box, a phonograph tone arm mounted upon the top of said box, a telephone receiver secured to a wall of said box adjacent the top thereof and supported by said wall, said bottom, top and wall each being provided with an orifice, said orifices aligning respectively with the sound tubes of said amplifier, said tone arm and said telephone receiver, a valve member 30 pivoted in the angle of said box between the top and the telephone receiver supporting wall of the same and adapted to be turned upon its pivot into alternate contact with said top and said wall to close alternatively communication between the sound tubes of said tone arm and said telephone receiver with the sound tube of said amplifier.

This specification signed this 4th day of 45
September, 1924.

FRANK OBERST.
